(57) **CLAIM**

The ornamental design for a weather-strip clip, as shown and described.

DESCRIPTION

FIG. 1 is a perspective view of the front, right side and top of a weather-strip clip showing our new design;

FIG. 2 is a front view thereof;

FIG. 3 is a right side view thereof, the left side view being identical thereto;

FIG. 4 is a top plan view thereof;

FIG. 5 is a bottom view thereof;

FIG. 6 is a cross sectional view at 6—6 thereof; and,

FIG. 7 is a cross sectional view at 7—7 thereof.

1 Claim, 7 Drawing Sheets

FIG. 1

FIG. 2

FIG. 3

FIG. 4

FIG. 5

FIG. 6

FIG. 7
